DESIGN FOR A RADIOCABINET

Mark Flaherty, Haddonfield, N. J., assignor to
Radio Corporation of America, a corporation of
Delaware

Application April 28, 1934, Serial No. 51,578

Term of patent 3½ years

To all whom it may concern:

Be it known that I, MARK FLAHERTY, a citizen of the United States and a resident of Haddonfield, in the county of Camden and State of New Jersey, have invented a new, original, and ornamental Design for Radiocabinets, of which the following is a specification, reference being had to the accompanying drawing forming a part thereof.

The figure is a perspective view of a cabinet embodying my new design.

I claim:

The ornamental design for a radiocabinet substantially as shown.

MARK FLAHERTY.
